UNITED STATES PATENT OFFICE.

JOHN PH. KERN, OF LOUISVILLE, KENTUCKY.

CARD AND LABEL HOLDER.

1,325,476.

Specification of Letters Patent. Patented Dec. 16, 1919.

Application filed December 20, 1918. Serial No. 267,665.

To all whom it may concern:

Be it known that I, JOHN P. KERN, a citizen of the United States, residing at Louisville, in the county of Jefferson and State of Kentucky, have invented new and useful Improvements in Card and Label Holders, of which the following is a specification.

My present invention pertains to devices for holding cards, labels and the like and detachably fixing the same to the edges of shelves and similar supports; and it consists in the peculiar and advantageous fastening holder hereinafter described and definitely claimed.

In the accompanying drawings, hereby made a part hereof:

Figure 1 is a front elevation of my novel device as it appears when positioned on the edge of a shelf and with a price label in the holder.

Fig. 2 is a vertical transverse section taken in the plane indicated by the line 2—2 of Fig. 1.

Fig. 3 is an end elevation of the device as it appears normally or precedent to its application to the edge of a shelf or the like.

Similar numerals of reference designate corresponding parts in all of the views of the drawings.

The shelf illustrated is designated 1, and may be a shelf of any description without affecting my invention.

2 is a card or price tag, designed to be connected to the edge of the shelf through the medium of my novel device, and this card or tag may be of any suitable material.

My novel card and label holder and fastening device is formed of a single piece of thin sheet metal, and is resilient in character. It comprises a body 3, lower and upper flanges 4 and 5, disposed parallel to the body 3 and in spaced relation thereto, and arms 6, which reach rearwardly from the said flanges. In forming the flanges 4 and 5 and the arms 6, the single sheet of metal is first bent upon itself at the upper and lower edges of the body or body plate 3, and the upper and lower extremities of the sheet are then carried rearwardly below and above the lower and upper edges of the body plate. It will also be observed that the arms 6, as well as the flanges 4 and 5, correspond in length to the body plate 3, and that normally the said arms 6 are rearwardly converged.

By virtue of this latter provision it will be observed that when the device is to be placed upon the edge of a shelf or similar support, it is necessary to spring the arms 6 outwardly into parallel relation. This will place the arms under tension and, consequently, when released, they will strongly clamp the opposite sides of the shelf and thereby preclude casual displacement of the device. When, however, it is desired to remove the device from a shelf, the same may be expeditiously and easily accomplished by drawing the device off the shelf, whereupon the arms 6 will resume their normal rearwardly converged state.

Inasmuch as the ends of the flanges 4 and 5 are open, it will be manifest that a card or label may be moved with facility into or out of either end of the holder, and this without liability of the card or label being displaced when the device is in use.

The important features of my novel device considered as a specific article of manufacture reside in the fact that it may be quickly and easily formed of a single rectangular piece of tin or other appropriate sheet metal, and in the fact that its formation does not entail the employment of expensive machinery and does not involve the exercise of more than ordinary care. Manifestly, the device may be cheaply produced, either by hand or with the assistance of a suitable mandrel and tools for shaping the sheet of metal on the mandrel.

Having described my invention, what I claim and desire to secure by Letters Patent, is:

As a new article of manufacture, a device for holding a card or a label in opposed relation to a shelf edge, formed of a single rectangular sheet of resilient material and comprising a body plate, lower and upper flanges spaced in front of and parallel to the face of the body plate and open at their ends; said flanges being formed by loops extending from the lower and upper edges of the body plate, and resilient arms joined to and reaching rearwardly from the outer layers of the flanges and disposed below and above the said loops and braced by the same, and normally converged toward their rear ends.

In testimony whereof I have affixed my signature.

JOHN PH. KERN.
